UNITED STATES PATENT OFFICE.

KURT EVERE, OF CHARLOTTENBURG, GERMANY, ASSIGNOR TO GENERAL ELECTRIC COMPANY, A CORPORATION OF NEW YORK.

INTERNAL-COMBUSTION ENGINE.

1,187,292.

Specification of Letters Patent. Patented June 13, 1916.

Application filed April 29, 1916. Serial No. 94,493.

To all whom it may concern:

Be it known that I, KURT EVERE, a subject of the King of Prussia, residing at Charlottenburg, Germany, have invented 5 certain new and useful Improvements in Internal-Combustion Engines, of which the following is a specification.

The present invention relates to two-cycle internal-combustion engines, especially those 10 of the high compression type in which the products of combustion are swept out of the cylinder by a blast of scavenging air, the pure air remaining in the cylinder being subsequently compressed by the instroke of 15 the piston to such high pressure that its heat ignites a charge of fuel injected in the cylinder. It is customary to start such engines by means of compressed air changing over to operation on fuel as soon as the final tem- 20 perature of the air pressed in the cylinder on the compression stroke is sufficiently high to ignite the fuel. This final temperature depends, among other things, upon the initial temperature and pressure of the 25 scavenging air at the beginning of the compressor stroke. The higher this initial temperature and pressure the higher, of course, is the final temperature and pressure. The scavenging air in such engines is 30 supplied to the cylinders from a suitable receiver to which air is supplied by an air pump, which may be operated from the crank shaft of the engine.

In starting engines of this type, the receiver pressure is much lower than the pressure of the starting air after it has performed its work in the cylinder and, as a consequence, the starting air will escape from the cylinder through the scavenging 35 ports into the receiver. Here it expands due to the lower pressure existing in the receiver, and as a consequence is materially cooled. This means that the scavenging air will thus become cooler. Consequently when 40 the scavenging air enters the cylinder at this lower temperature it may not reach a sufficiently high temperature upon the compression stroke to cause the ignition of the fuel which is introduced. This tends to 45 retard the starting of the engine.

The object of the present invention is to provide an improved arrangement which will prevent the starting air during the starting period from expanding into the receiver. To this end I provide in connection 55

with the scavenging ports, a suitable valve mechanism for cutting off communication between the receiver and the scavenging ports. This valve mechanism is closed during the starting period. At the end of the 60 starting period it is opened, either manually or automatically.

My invention is applicable to either single cylinder or multi-cylinder engines. With a single cylinder engine a suitable valve 65 mechanism for the purpose stated will, of course, be applied to such cylinder. In the case of multi-cylinder engines it is customary to provide only a part of the cylinders with air starting means, and in connection 70 with such engines the valve mechanism will, therefore, be applied only to the cylinders which are so equipped. Of course should all the cylinders of a multi-cylinder engine be provided with air starting means, then 75 I would also preferably provide each with a valve mechanism.

In the accompanying drawing, Figure 1 is a diagrammatic sectional view of a two-cycle high compression multi-cylinder engine embodying my invention, and Fig. 2 is 80 a detail view of a valve mechanism.

Referring to the drawing, 3 and 4 indicate the cylinders of a multi-cylinder engine. In the present instance two cylinders are 85 shown, but it will be understood that more than this number may be used. Each cylinder contains oppositely moving pistons 5 and 6 which act on the same crank shaft, the upper piston controlling the exhaust ports 7 and the lower pistons the scavenging or air charging ports 8, to which air is admitted from the receiver 9 which surrounds the cylinders. The scavenging pump 10 delivers air into the receiver 9 through the valves 11. The exhaust ports 7 are connected with a common header or manifold 12 through suitable branch pipes. The crank shaft of the engine is not shown in the drawing, but it will be understood that the connecting rods 13 for the lower piston 6 and the side rods 14 of the upper pistons 5 are suitably connected thereto, as is also the connecting rod 15 of the air compressor 10. 90 16 indicates an opening in the cylinder wall of each cylinder through which fuel is injected into the cylinders. It will be understood that a suitable fuel injector is connected with these openings as is customary. In the present instance only the cylinder 3 is shown 105 110

as being equipped with an air starting valve, such a valve being diagrammatically illustrated at 17. To shut off the receiver 9 from the scavenging ports of this cylinder during the starting operation I have shown the receiver 9 which surrounds the cylinder 3 as being provided with a partition plate 18 having spaced ports 19 therein. Located on this partition plate is an annular ring valve 20 having ports 21 which may be moved into and out of registering position with the ports 19. The ring valve is provided with a series of gear teeth 22 upon one side with which meshes a small pinion 23, which pinion is operated by the rod 24 and hand wheel 25. The ring valve may be held in place and guided in its movement by means of lugs 26 which project over the top of it.

During the starting operation, the hand wheel 25 will be turned to bring the ring valve into a position where it closes the ports 19. The starting air is thus prevented during the starting period from expanding into the receiver 9. The engine will be started in the usual manner, and after it attains sufficient momentum to compress the air so as to fire a charge, or in the case of a multi-cylinder engine after some of the cylinders begin to fire, the hand wheel 25 will be operated to move the ring valve to open the ports 19 and thus connect the receiver 9 with the scavenging ports 8 of the cylinder or cylinders as the case may be.

It will, of course, be understood that the drawing is only illustrative of my invention and that various valve arrangements may be used to suit any particular design of engine.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. The combination with an internal-com-

bustion engine, of a receiver connected therewith for supplying scavenging air to the engine, means for admitting compressed air to the engine for starting it, and means for shutting off the scavenging ports from the receiver during the starting period to prevent the starting air from expanding into the receiver.

2. The combination with an internal-combustion engine, of a receiver connected to it for supplying scavenging air thereto, means for admitting compressed air to the engine for starting it, and valve mechanism for shutting off the scavenging ports from the receiver during the starting period to prevent the starting air from expanding into the receiver.

3. The combination with a multi-cylinder internal-combustion engine, of a receiver for supplying scavenging air thereto, means for admitting compressed air to a part of the cylinders for starting the engine, and means for shutting off the scavenging ports of such cylinders from the receiver during the starting period.

4. The combination with a multi-cylinder internal-combustion engine, of a receiver for supplying scavenging air thereto, means for admitting compressed air to a part of the cylinders for starting the engine, and valve mechanism for shutting off the scavenging ports of such cylinders from the receiver during the starting period.

5. In an internal-combustion engine, the combination of a plurality of cylinders having exhaust and scavenging ports, a receiver connecting with the scavenging ports, fuel admission means, valve means for supplying starting air to some of said cylinders, and means for cutting off communication between the receiver and the scavenging ports of the cylinders having said valve means.

In witness whereof, I have hereunto set my hand this 17 day of March, 1916.

KURT EVERE.
